CLAIM

The ornamental design for a storage device, as shown and described.

DESCRIPTION

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

FIG. 1 is a perspective view of a storage device embodying one aspect of our new design;

FIG. 2 is a front elevational view of the storage device of FIG. 1;

FIG. 3 is a rear elevational view of the storage device of FIG. 1;

FIG. 4 is a right side profile view of the storage device of FIG. 1, it being understood that the left side profile view is a mirror image;

FIG. 5 is a top plan view of the storage device of FIG. 1; and,

FIG. 6 is a bottom plan view of the storage device of FIG. 1.

The subject matter shown in broken lines is directed to environment and forms no part of the claimed design.

1 Claim, 6 Drawing Sheets
